UNITED STATES PATENT OFFICE.

SPENCER OTIS, OF BARRINGTON, ILLINOIS.

TEMPERATURE-MAINTAINING MEANS FOR BOILER-FILLING APPARATUS.

Original application filed January 29, 1920, Serial No. 354,767. Patent No. 1,480,737, dated January 15, 1924. Divided and this application filed June 8, 1923. Serial No. 644,290.

This application is a division of application Serial No. 354,767, filed January 29, 1920, which has matured into Patent No. 1,480,737, January 15, 1924.

5 This invention relates to apparatus for delivering hot water from a supply tank to a boiler, for instance, a locomotive boiler, which is being filled, and particularly to a means embodied in such apparatus whereby the temperature of the water in the filling tank may be kept up to a desired degree.

10 The apparatus with which the present invention is immediately concerned usually forms part of a system which involves means for receiving and salvaging heat units and hot water from the products blown off from locomotive boilers, the salvaged heat, separated in the form of vapor or steam, being absorbed in condensing water which passes to a storage tank for filling water at a temperature suitable for boiler filling purposes, and the salvaged water being collected in another tank for use in washing out boilers; and in systems 15 of this kind it is usual to employ steam pumps for advancing water from the respective tanks to locomotive stalls where the water is consumed, and to have a return flow pipe or circulating line in series with the filling water supply line which leads back to the filling water tank, so that a 20 low capacity circulation will be maintained through the filling line even when water is not being consumed and thus keep up the 25 temperature at the points of consumption.

30 It has further been the practice, prior to the present invention, to bring together the water returned by the circulating line and steam exhausted from the pumps which 35 advance the filling and washout waters, and thereby compensate for heat lost by radiation during the circulation of the filling water. But the system as here outlined, under some conditions, does not sufficiently 40 compensate for drop of temperature of the filling water, if consumption of filling water is particularly large, and there is no return flow through the circulating line during a 45 large proportion of the time.

50 Now, the object of the present invention is to provide means whereby, whenever the

temperature of water issuing from the filling tank is below a predetermined degree, a portion of the output of the pump will be by-passed or short circuited back to the 55 tank through a relatively short path in which losses by radiation are negligible, and in the course of which it meets and absorbs steam, preferably exhaust steam from the pumping engine or engines, sufficient in 60 volume to restore the temperature of the tank to the degree appropriate for filling purposes.

The accompanying drawing represents a 65 diagrammatic view, in side elevation, of separating, condensing, and filling water storage elements of a boiler washing system, together with parts immediately necessary thereto, and among which are embodied the features of the present invention. 70

1 represents a blowoff pipe of a boiler washing system which receives the products blown off from a locomotive, or other boiler, and delivers the same to a separator 2, whence steam or vapor will escape through 75 a pipe 3 to a condenser 4 where a spray of cold water will be released into absorbing relation thereto by means of thermostat 5 controlling valve 6 in cold water spray pipe 7, and from which condenser resultant hot 80 water escapes through a pipe 8 to filling tank 9. Incidentally, condenser 4 may likewise be equipped with live steam pipe 10 having a valve 11 under control of an outside float 12, so that whenever the water 85 level in tank 9 reaches a predetermined point, live steam will be released to the condenser 4 and, in turn, act upon the thermostat 5 and release condensing water to pipe 7 until such time as the level in the filling tank rises sufficiently to close the steam valve 11 by the settling of the outside float 12.

13 represents a pump which receives hot water from tank 9 through a pipe 14 and 90 discharges the same through a pipe 15 leading to convenient points of consumption in the locomotive house. As is usual in systems of this kind, a throttle valve 16, which controls the engine of pump 13, will be 95 under control of a pressure valve 17 in communication with delivery pipe 15 of the

pump, so that the output of the pump will be restricted to the consumption on the line; that is to say, if water is discharging freely from the line 15, steam pressure will 5 be proportionately increased and the output of the pump enlarged to meet the demand. 18 represents a circulating line or return flow pipe of reduced capacity which receives water from the filling line 15 and brings 10 it back toward the tank, or, as has been proposed prior to the present invention, delivers return flow water to an auxiliary condenser 19 where the return flow water meets steam delivered thereto by the 15 exhaust pipe 20 of the steam pump 13, thereby saving the heat units of the exhaust steam and restoring to the water of circulation, temperature that it may have lost by radiation in its path through the pipes 20 15 and 18.

It sometimes happens that the system of circulation as thus far described is not sufficient to keep the temperature of filling water in tank 9 up to the degree desirable 25 for boiler filling purposes, particularly when the drain on pipe 15 for boiler filling purposes is such as to interrupt the return flow through pipe 18. The present invention remedies this defect by short circuiting 30 or by-passing a sufficient proportion of the output of the pump 13 back to the tank 9 through a by-pass pipe 21 branching from the filling line 15 through a thermostatically controlled valve 22, and discharging 35 into a suitable condenser, preferably the auxiliary condenser 19, where it meets a steam supply, preferably exhaust steam from the pump 13, so that without interrupting the delivery of water over the filling line 15, a portion of the water in tank 40 9 will be circulated through a heater and back to the tank, the temperature of water in the tank being thereby restored. The by-pass valve 22 is opened by a thermostat 45 23 in the intake pipe 14 of the pump, and is adjusted to react and open the valve 22 whenever the temperature of the water in the pipe 14 is below a predetermined degree. The flow of hot by-passed water from the 50 auxiliary condenser 19 back to tank 9 is through pipe 24 to the pipe 8 which leads from the main condenser 4 to the tank 9, as already explained.

I claim:

55 1. In a boiler filling apparatus, having a tank and a channel through which water flows from said tank to a place of consumption, a by-pass channel leading from the channel first-named back to the tank 60 and having a valve, a thermostat controlling said valve and which is controlled by the temperature of water issuing from the tank, through the channel first named, and means for heating water returning to the tank 65 through said by-pass channel.

2. In a boiler filling apparatus, a tank, a filling line for delivering water from said tank to a boiler, a by-pass channel leading from the filling line back to the tank, a valve controlling said by-pass channel, a 70 thermostat subject to temperature influence of water issuing from the tank, controlling said valve, and a heater forming a part of said channel.

3. In a boiler filling apparatus, a tank, a filling line for delivering water from said tank to a boiler, a by-pass conduit leading from a portion of the filling line adjacent to the tank back to the tank, a heater interposed in said conduit, a valve for opening and closing communication between the conduit and the filling line, and a thermostat controlling said valve located in the filling line between said valve and the tank. 75

4. In a boiler filling apparatus, a tank, a filling line for delivering water from said tank to a boiler, a by-pass pipe communicating with said filling line, a valve controlling such communication, a thermostat subject to temperature effect of water flowing in 90 the filling line, a condenser into which the by-pass pipe discharges and which in turn delivers back to the tank, and means for supplying steam to said condenser. 85

5. In a boiler filling apparatus, a tank, a filling line for supplying water from said tank to a boiler, a pump interposed in said line, a by-pass pipe connected with said line on the other side of the pump from the tank, a thermostat inserted in said line between 100 the pump and the tank, a valve controlling communication between the by-pass pipe and the filling line, said valve being controlled by said thermostat, a heater adapted to raise the temperature of water passing 105 through said by-pass pipe, and a channel of communication for water so heated which leads back to the tank. 105

6. In a boiler filling apparatus, a tank, a filling line for supplying water from said tank to a boiler, a pump interposed in said line, a by-pass pipe connected with said line on the other side of the pump from the tank, a thermostat inserted in said line between 110 the pump and the tank, a valve controlling communication between the by-pass pipe and the filling line, said valve being controlled by said thermostat, a heater adapted to raise the temperature of water passing 115 through said by-pass pipe, and a channel of communication for water so heated which leads back to the tank; there being a steam engine for actuating said pump, and the exhaust steam from said engine being delivered to said heater. 120

7. In a boiler filling apparatus, a tank, a filling line for delivering water from said tank to a boiler, a pump forcing water through said filling line, a return flow line receiving water from said filling line, a 130

heater adapted to act upon water returned through said return flow line, a channel through which return water thus heated reaches the tank, a by-pass channel delivering filling water through said heater from a point near the pump, a valve controlling flow of water through said by-pass channel

and a thermostat controlling said valve and subject to temperature influence of water flowing in the filling line. 10

Signed at Chicago, Illinois, this 4th day of June, 1923.

SPENCER OTIS.
